C. W. LE VELLE

DISAPPEARING ELECTRIC FAN MECHANISM

Filed July 31, 1922

FIG. 3

FIG. 1

INVENTOR.
Clarence W. LeVelle
BY

U. G. Charles ATTORNEYS.

Patented June 12, 1923.

UNITED STATES PATENT OFFICE.

CLARENCE W. LE VELLE, OF WICHITA, KANSAS.

DISAPPEARING ELECTRIC-FAN MECHANISM.

Application filed July 31, 1922. Serial No. 572,763.

To all whom it may concern:

Be it known that I, CLARENCE W. LE VELLE, a citizen of the United States, residing at Wichita, in the county of Sedg-

wick and State of Kansas, have invented certain new and useful Improvements in Disappearing Electric-Fan Mechanisms, of which the following is a description, referring to the drawings which accompany this

10 specification.

The invention relates to that class of electrical ceiling fans as described in my pending application for Letters Patent, filed March 6, 1922, Serial No. 541422 and in

15 which both the fan proper and its motor are mounted upon and supported by a pipe suspended from a ceiling, beam or the like.

In the class of fan referred to in my pending application and to which the present application closely relates, the fan blades are through spring controls rendered invisible by concealment with the mechanism; thus they form a more suitable and more beautiful fixture than fans which are permanently in view. Electric lighting sockets may be affixed on the mechanism as readily understood; thus one ceiling opening will serve for fan and lighting purposes if so desired.

20 In the previous fan constructions of this character, the centrifugal action of the fan and the spring controls, did not always function the same for each unit fan blade; in the present invention this objectionable feature is fully discussed and means provided whereby a coaction occurs and continuously exists between the several unit fan blade assem-

blages and whereby all the blades present themselves simultaneously for fan action and similarly fold within the mechanism for concealment when not in action.

This principal feature of the invention will be most readily understood by reference to the accompanying drawings in which Fig. 1 shows a top plan view of the motor and showing the radial mechanisms on which pivot the unit fan sections; and the combination effected by the unified wire control of the several parts. Fig. 2 shows a plan view

45 of a radial bracket element, detached and with the wire connections made thereon. Fig. 3 is a side view of Fig. 2 without the wire elements. Fig. 4 is a perspective view of a stop element seen in Figs. 2 and 3.

50 Fig. 5 is a bottom view of Fig. 3 to show the spring mechanism for effecting desired

spring controlled movements. Similar numerals of reference indicate corresponding parts throughout all the figures of the drawings.

60

Referring to the drawings, the fan fixture support consists of a tubular hanger 1 suspended from a ceiling (not shown). This hanger 1 is the nonrotary shaft of the motor 2, which is of the revolving field type such as is customarily employed in similar installations. The upper and lower canopies as carried by my similar illustration in the pending application above mentioned are not in this invention illustrated since they 70 form no specific function in the present invention, but mention may be properly made to the fact that when employed the blade elements, later disclosed, operate to open outwardly or fold inwardly between such canopies and against the motor when folded in.

75 A metal ring 3 is rigid with the frame of the motor 2 and is driven thereby. A plurality of bracket members 4, are rigidly affixed at spaced intervals upon the periphery 80 of the ring 3. Each member 4 receives a screw element 5 of a stationary circular member 6. The member 6 is provided with a vertical shaft 7 upon which the cap element 8 pivotally moves. An arm element 8x outwardly projects from the member 8. A fan blade 9 is rigidly attached in the finished mechanism to each arm element 8. Only one blade 9 however is shown in Fig. 1 for 90 convenience of illustration but it is to be understood that each arm 8 is provided with such a blade 9.

95 The stop element shown in Fig. 4 is a curved plate 10 with an upper cut away portion 11 to provide a shoulder 12 as illustrated. The screw 13 when backed off permits the plate 10 to be moved to a desired position, the screw then is screwed down so that its head presses down upon and retains the stop 10 in a proper position. Roller or ball bearings may be used in conjunction with the pivoting mechanism within the parts of the cap member 8x and the stationary member 6. Thus it will be seen that each cap member 8x will pivot outwardly 100 under centrifugal force to the position illustrated for each as seen in Fig. 1 and to a contact with the stop 12. Thus each blade 9 of proper curved and warped configuration is in functional operation for fan 110 purposes.

Now in order that there may be a simulta-

neous folding of the blades inwardly against the motor when it is inoperative, the blades are hollowed out as at 9^x so that when movement of the blade inwardly is occasioned, 5 shown by the dotted arc, the arms 8 also follow their dotted arcs similarly so that each hollowed portion blade portion 9^x will member around the motor 2.

10 In order that each blade will be in the same proper position as every other blade of the assembly at each instant of operation or closure, I, in the present invention, link the several elements 8^x together so that when one moves, all move a corresponding degree, thus 15 each blade 9 similarly moves just as its companion blades do. The spring 13 normally tends to draw its blade 9 into the folded position against the motor, or to a contact by a part 8^x with the stop 12. But 20 each spring might not exert the same tension for this movement hence by the linking together all of the parts, all springs will work in unison; similarly all blades might not move just as fast to assume their outwardly 25 thrown position, so that the linking together exerts a proper control so that they must so function.

1 Referring to Figs. 1 and 2 a wire or cable 14 engages around all the cap elements 8^x. 15 Each cap element has two binding posts or screws 15, 16; the cable 14 leading as at 14^x around to the post 15, thence back to the post 16 thence outwardly as at 14^y. The posts are properly spaced to permit of sufficient 20 lap of the cable elements so that a pull from either direction will cause a proper tendency of the cap member 8^x to pivot. It will thus be seen that since the cable 14 engages all 25 posts 15 and 16 of the assemblage, that each 30 blade element moves both in or out with its companion blades and simultaneously therewith.

Various modifications may be employed 35 as lie within the scope of the appended 40 claims. Having fully disclosed my invention 45 what I now claim as new and desire to secure by Letters Patent is;

1. In a motor driven fan, a motor having a vertical axis, a rotatable element concentric

50 with said axis; a plurality of radial elements on said element each radial element having pivotable elements and linking means for uniting said pivotable elements for simultaneous pivoted movements.

55 2. In a motor driven fan, a motor having a vertical axis, a rotatable element concentric with said axis; a plurality of radial elements on said element; each radial element 60 including a blade carrying an element pivotally mounted on said radial element and a cable means engaging around and to each blade carrying element for unified controlled pivoted movements.

65 3. In a motor driven fan, a motor having a vertical axis, a rotatable ring concentric with said axis; a plurality of bracket elements 70 radially disposed from said ring; each bracket member supporting a cap element pivotally mounted to rotate thereupon, an arm rigid with said cap element and a blade 75 rigid with said arm; and linking means engaging each cap element for controlling and unifying their pivoted movements.

80 4. In a motor driven fan, a motor having a vertical axis, a rotatable ring concentric with the axis; a plurality of bracket elements 85 radially disposed from said ring; each bracket member carrying an adjustable stop member, a cap member pivotally mounted to move on elements carried by said bracket member, an arm rigid with said cap member, means on the cap for limiting the amount of pivoted movement in either direction by its contact at spaced pivoted positions with said stop element, a fan blade on said arm; a cable leading to a binding post on said cap element, thence backwardly to another post on said cap element, thence outwardly to a similar connection in turn with each other cap element and to a connection 90 from the point of beginning; and whereby any pivoted movement of one fan blade element is simultaneously transmitted to each and every other fan blade element so that a unified and controlled pivoted movement of 95 all fan blades is had for the purposes of the invention.

CLARENCE W. LE VELLE.
